UNITED STATES PATENT OFFICE.

GEORGE R. MEISSNER, OF ALBIA, IOWA, ASSIGNOR TO L. R. WEST, OF OSCEOLA, IOWA.

CIGAR-HOLDER.

1,252,357.

Specification of Letters Patent. Patented Jan. 1, 1918.

Application filed November 3, 1915. Serial No. 59,438.

To all whom it may concern:

Be it known that I, GEORGE R. MEISSNER, a citizen of the United States, residing at Albia, in the county of Monroe, State of Iowa, have invented certain new and useful Improvements in Cigar-Holders; and I do hereby declare the following to be a full, clear, and exact description of the invention, such as will enable others skilled in the art 10 to which it appertains to make and use the same.

This invention relates to combined cigar holders and pipes and it has for its object to provide a structure embodying a removable pipe bowl which when in position will hold loose tobacco and will assist in holding a cigar in erect position and in which furthermore when the bowl is removed the cigar may be held in horizontal position 20 while the device is in use.

Referring to the drawings, forming a part of the application:

Figure 1 is a side elevation of my improved holder.

Fig. 2 is a longitudinal section.

Fig. 3 is a detail view of the supporting ring, and

Fig. 4 is a vertical longitudinal section, showing the pipe bowl connection with the 30 device.

Referring to the drawings, the numeral 5 designates the drawing stem, preferably constructed of metal tubing, having the usual push type mouth piece detachably connected at one end. The stem 5 extends from the mouth piece 6, and is laterally directed and coiled to form the finger receiving loop or ring 7, and the free end is screw-threaded for the reception of a bulb 35 8, which has screw-threaded connection, so that it may be readily removed to discharge the saliva accumulated therein. The ring 7 at its central lower part is provided with an opening 9 communicating therewith and 40 adapted for the reception of a second saliva collecting bulb 10.

On its upper edge at the central part thereof, the ring 7 is provided with a threaded aperture 11, in which is mounted the 45 socket projection 12, having interior and exterior screw threads 13 and 14. This socket projection 12 is adapted to receive the lower correspondingly threaded end 15 of the tubular conical shaped impaling member 16, 50 having a pointed upper end adapted to pierce the cigar 17 for the purpose of re-

taining the cigar on the stem 5. The impaling member 16, below its pointed end is provided with openings 18, through which smoke passes into the stem. 60

The horizontal part of the stem is provided with an adjustable ring 19, having its lower ends clamped on the stem, and is adapted to support that part of the cigar back of the impaling member 16. The ring 65 19 may be moved up nearer to or farther away from the impaling member to accommodate cigars of different lengths and support same until only the butt is left, after which the butt may be inverted and impaled on the 70 impaling member, which projects upwardly through the heretofore closed end of the cigar, and thus the entire cigar may be consumed.

To permit of smoking of loose tobacco, a 75 pipe bowl 20 is provided having an aperture equipped with an interior bushing 21 which may be screwed onto the threads of the projection 12. At this time the impaling member 16 may be removed. When, 80 however, it is desired to smoke a cigar standing on end, the impaling member is permitted to remain and the cigar struck into the bowl of the pipe and onto the impaling member, the pipe bowl serving to hold the 85 cigar in this position.

It is obvious that a holder embodying my improved construction may be held by passing the index finger through the ring with the thumb engaging the point of intersection of the horizontal portion of the stem and the ring, and this is more particularly of value to automobilists whose hands are employed in gripping the wheel, and at the same time the holder may be supported on 90 the index finger when not in use. 95

Likewise the holder by its ring construction, provides a means for cooling the smoke passing therethrough, collecting of the saliva and the conversion of a holder into a 100 pipe.

From the foregoing description, taken in connection with the accompanying drawings, the advantages of the construction and the method of operation will be readily apparent to those skilled in the art to which the invention appertains, and while I have described the principle of operation of the invention, together with the device which I now consider to be the embodiment thereof, 105 I desire to have it understood that the device shown is merely illustrative, and that 110

such changes may be made when desired as are within the scope of the claim appended hereto.

Having thus described my invention, what I claim as new, is:

A combined cigar holder and pipe comprising a stem having a tubular extension projecting therefrom at an angle and communicating with the interior of the stem and interiorly and exteriorly threaded, a threaded impaling member removably engaged with the interior threads of the extension and adapted to engage into either the side or the end of a cigar and a pipe

bowl having an axially threaded opening 15 in its bottom in which the threaded projection is removably screwed and into which bowl the impaling member projects axially, said bowl when in position being adapted to interchangeably hold loose tobacco or 20 hold a cigar against lateral movement when axially impaled upon the impaling member.

In testimony whereof, I affix my signature, in the presence of two witnesses.

GEORGE R. MEISSNER.

Witnesses:
